UNITED STATES PATENT OFFICE.

OSCAR J. LAISY, OF CLEVELAND, OHIO.

AIRSHIP.

1,189,138.

Specification of Letters Patent. Patented June 27, 1916.

Application filed September 21, 1912. Serial No. 721,584.

To all whom it may concern:

Be it known that I, OSCAR J. LAISY, a citizen of the United States, residing at Cleveland, in the county of Cuyahoga and 5 State of Ohio, have invented a certain new and useful Improvement in Airships, of which the following is a full, clear, and exact description, reference being had to the accompanying drawings.

10 This invention relates to air ships of the dirigible balloon type.

One of the objects of the invention is to provide, in a very efficient and light form a balloon constructed so as to be very strong 15 and thoroughly braced to meet all strains to which it may be subjected.

Other objects are to so arrange the balloon that it may be rotated for purposes of propulsion, may be automatically compensative 20 for changes of temperature, and may be easily collapsed for packing and easily erected for inflation.

These, and other features which contribute to the efficiency of my air ship are hereinafter more fully described and definitely summarized in the claims.

In the drawings, Figure 1 is a side elevation of my air ship; Fig. 2 is a cross section of the balloon through the air bag adjacent 50 to the central set of the spokes; Fig. 3 is a longitudinal central section of the balloon; Fig. 4 is a cross section showing the truss arrangement of wires which hold upright the vanes; Fig. 5 is a longitudinal section of 55 the rear end of the balloon; Fig. 6 is an end view of the same; Fig. 7 is an enlarged detail of the compensative valve; Fig. 8 is a detail of an arrangement for holding the rib wires of the vanes; Fig. 9 is a plan of 40 the same; Fig. 10 is a detail of a bracket by which the outer end of each spoke is attached to the canvas of the balloon; Fig. 11 is a bottom plan of the same on the side to which the spokes are attached; Fig. 12 is a side 45 elevation of the bracket; Fig. 13 is a detail illustrating a modified form of vane support.

My balloon is built with a central, longitudinal lattice-work shaft 1, which is shown 50 as formed of four longitudinal corner strips 2, of wood or other light material, at right angles to which are cross braces forming a box truss of the Pratt type. This truss is braced and stiffened by diagonal wires 4 55 tightly drawn between the joints of the cross braces 3. By this construction I have a light

but very strong and rigid shaft on which to construct a balloon of this kind. Carried on this shaft are several rings 7 which carry the spokes 8 adapted to project to the canvas 60 of the balloon and be secured thereto. My drawings show three sets of these spokes 8, although any convenient number may be employed.

From the two outermost set of spokes 8, 65 the balloon tapers substantially to the shaft, where the canvas terminates in air-tight fastenings on the heads or rings 9 and 10. To allow for the collapsing of the balloon, the spokes 8 are pivoted to the rings 7 and 70 adapted to fold toward the rear of the shaft 1, carrying the canvas of the balloon with it, somewhat as an umbrella is closed. This causes the head 9 and the ring 11 to slide a short distance along the shaft 1 as the 75 spokes nearest this end fold away from it. The head 9 is previously loosened from the adjacent sheave to permit this movement in a manner to be described later.

The form of the balloon when inflated is 80 substantially that of a cylinder terminated in a cone at each end. To give rigidity to the balloon and best retain its shape, I stretch wires 13 longitudinally from the ring 9 over the outer end of a spoke 8 in each of 85 the sets of spokes and attach it at the head 10 at the other end of the balloon. I also use a convenient number of wires 14 which run spirally in opposite courses around the balloon and are attached to the canvas by 90 tapes sewed on either side of the wire, or are embedded between two thicknesses of canvas. Some or all of these spiral wires may be attached at sections to the ends of the spokes and these wires, with the circumferential and longitudinal wires, form, in 95 effect, a net supporting the canvas. These wires may be also suitably fastened to the canvas at some of the points of their intersection by small washers on the inside and outside of the canvas, in a manner to be 100 described later. These spiral wires may be inside or outside of the canvas. Wires 16 are shown in Fig. 2 as drawn over the end of every third spoke, and these help distribute the tension of the spiral wires 14. 105 Wires 17 extend longitudinally between corresponding spokes in each set a short distance in from the canvas. Wires 12 are attached to the ring 11 and extend through the hub 7 nearest the forward end and loosely through the ring 9 (so as not to in-

terfere with its movement along the shaft) and serve to hold the ring 11 in its forward position when the balloon is inflated.

Secured to the canvas at some of the intersections of the longitudinal wires 13 with the spiral wires are short spokes 18 which carry the wire extension 19 (Figs. 8 and 9). On these extensions 19 are spiral blades or vanes 20 made of cloth sewed to the canvas and over wires 21, carried at the outer ends of these wire extensions 19, the spiral passing continuously from any spoke 18 to the one next to the right or left in the next set. By this means, light and efficient propellers are formed on the outside surface of the canvas, and, as the balloon is rotated, these propellers cause it to move through the air in one direction or the other.

The spokes 18 are braced by wires 22 extending around the interior of the balloon and secured alternately to the foot of one spoke and to the next spoke, where they are attached by washers to the canvas, as shown in Figs. 8 and 9.

25 The balloon is rotated by means of a suitable cable 24 extending from a suitable driving mechanism indicated conventionally at 25, over groove pulleys or sheaves 26 and 27, which are rigidly attached to the heads 9 and 10. The head 9 being held by bolts, or other suitable detachable means to the sheave 26 allows the head 9 to slide along the shaft 1 when the balloon is folded.

30 The driving mechanism 25 is suitably mounted on a light frame 30 suspended by rods 31, 32 from brackets 34 and 35. From his position near the driving mechanism the operator has within easy reach a lever 37, by which he controls a suitable rudder 38.

40 Changes of temperature cause expansion and contraction of the gas within a balloon and are thus liable to put an undue strain on the canvas. To overcome this I provide an internal air-bag formed of cloth surrounding the shaft, and secured around the spokes 8. This air bag is connected by elastic cords 41 with the brace wires 42 extending from the central set of spokes at their outer ends to the hub 7 and the slidable ring 11 of the two other sets of spokes. A tube 45 is placed substantially along the axis of the shaft 1 and supplies the connection from the air bag to the outer air. A suitable valve 46, hereinafter explained in detail, 45 allows the air to pass either out of the air bag or into it whenever the excess of pressure within the bag or in the atmosphere is a predetermined amount. By the described means, when the gas in the interior of the balloon, and on the outside of the air bag, increases in pressure, as, for example, from the heat of the sun, it collapses the air bag, forcing some of the air out through the exit tube 45 and relieving the internal pressure. 60 When the pressure of the gas is reduced, as

in reaching a colder air stratum, the elasticity of the cords 41 draws the air bag back to its normal position, the air coming into the bag through the tube 45.

The valve 46, which allows the air to pass 70 either way, according to excess of pressure, while preventing too rapid a passage of the air, is shown in Figs. 5 and 7. It consists of a box 46 secured to the tube 45 and having an internal flange 47 with an inclined 75 edge. Bearing against this edge is an annular ring 48 which is normally held in place by the springs 50. The inner edge of this ring 48 is beveled in the opposite direction to that of the outer edge. Resting in 80 this bevel is a disk 51, held in place by springs 52. By this means, when the superior pressure is in one direction, the disk and inner ring move away from the outer ring to allow the air to pass through the 85 annular space thus provided; when a superior pressure is in the other direction, the disk itself moves away from the inner ring, allowing the air to pass between them.

90 The brace wires 42 above mentioned, being attached to the slidable ring 11 may be brought to tension by drawing the ring 9 to the sheave 26 by means of the bolts, as shown. It will be seen that this would tighten the bag back of the middle set of 95 spokes, as well as from these spokes forward to the ring 9, by tightening the spiral and longitudinal wires attached to the ring.

95 The exit from the valve box 46 is through a central tube 55 carried by the head 10. Surrounding this tube is a ball bearing hub 56, over the end of which is screwed a cap 57 having a hole 58 to allow the free passage of air into the tube 55.

100 The bracket 35 which supports the frame 105 30 at the rear end of the balloon is formed of straps 60 and 61 passing around the hub 56 and having at their end a cross brace 62 which is attached to the ends of the rods 32. This brace 62 extends outwardly at its central portion, forming a loop 63 suitable for a support for the upper pivot of the rudder 38. To reduce the strain on the straps 60 and 61, I provide small rollers 64 mounted on the strap 60 and adapted to bear against 110 the face of the sheave 27. The bracket 34 at the opposite end is similar to the one just described, except no provision is necessary for a rudder, and the cap 59 on the hub 54 may be removed for inflation of the balloon. 115 120

125 To provide for the convenient inflation of the balloon from a folded or deflated position, I provide a cylindrical sleeve 65 of any stiff material over which the ring 9 slides tightly to prevent the escape of gas. This is also air tight where it is joined to the sheave 26. Thus, when gas is forced into the passage through the hub 54 the ring is slid manually along the sleeve 65 until the balloon is fully inflated when the ring is 130

made fast to the sheave 26 by bolts or other suitable means.

Figs. 8 and 9 show a convenient method of fastening the canvas to the cross wires 13 and 14 at their points of intersection, and also a suitable manner of mounting the short spokes 18 with their extensions 19. In Fig. 8, 70 is a head having a flange bearing against a rubber washer 72 on the outside 10 of the canvas. Inside of the canvas is another rubber washer bearing against the wires at their points of intersection. On the inside of this series of washers and bearing against the inside of the wires is a metal 15 plate 73 having holes in its periphery, to which are attached the wires 22. The washers of this series are fastened together in any suitable manner, and it is seen that no holes through the canvas are necessary except to 20 admit the small wire 19, and perhaps rivets holding the washers together. At the ends of some of the spokes I provide staples 79 (Fig. 10) which replace two of the rivets and provide means for attaching ropes to 25 hold the air ship to the ground.

A convenient and efficient method of fastening the spokes to the canvas at their outer ends is shown in Figs. 10, 11 and 12. 75 indicates a disk having two ears at right angles to it (shown as stamped out of it), between which the end of the spoke 8 stands and is attached by a pin 76, thus forming a pivotal joint permitting the collapsing of the balloon. This disk 75 is set opposite a 30 rubber washer 74 through which the wires pass, as in Figs. 8 and 9. On the outside of the canvas opposite this disk and rubber washer is another disk, the whole being held together by rivets or other suitable means.

Fig. 13 illustrates another method of supporting the rib extension 19. 80 indicates a wire looped through the clip 81 on the wire 17 and passing through ears 82, similar to the ears 78 of the disk 75, forming a pivotal 45 connection or support allowing the vane 20 to remain upright when the balloon is collapsed.

It will be seen from the foregoing description that the balloon I have provided, 50 while being collapsible for transportation, is exceptionally well braced when distended. The wires, extending in the various directions described, resist all the strains to which the balloon may be subjected; at the same 55 time they do not add materially to the weight, because they are individually of small gage and very light.

Having thus described my invention, what I claim is:

1. In an air ship, a gas bag, a shaft extending longitudinally therethrough, rings carried by said shaft, a series of poles radiating from said rings, means for attaching the gas bag to the outer ends of said poles, truss wires connecting the outer ends of ad-

jacent poles and truss rods connecting said truss wires with the gas bag intermediate the poles whereby the bag is held distended.

2. In an air ship, a gas bag, propeller blades extending spirally about the exterior 70 of the gas bag, a series of wires extending longitudinally of the gas bag within the latter, means for attaching the wires to the gas bag, and a supporting wire projecting from the attaching means for holding the 75 blades.

3. In an air ship, a gas bag, a series of blades extending spirally about the exterior of the gas bag, a series of wires extending longitudinally of the gas bag within the latter, a series of clamping buttons for attaching the latter wires to the gas bag, and supporting wires projecting from the buttons for holding the blades.

4. In an air ship, a gas bag, a series of 85 wires extending longitudinally of the gas bag, a plurality of disks each having a stud, said stud extending through the gas bag from the interior, elastic washers surrounding the studs on the inner side of the gas 90 bag, means for compressing the elastic washers against the gas bag, and means for securing the said wires to the disks.

5. In a balloon, the combination, with a gas bag, of pivoted supporting spokes for 95 holding the gas bag distended or allowing it to collapse.

6. The combination, with a shaft, of spokes pivoted thereto and adapted to be folded down along the shaft or extending 100 outwardly, and a canvas bag enveloping the shaft and having its ends connected therewith and secured intermediately to the spokes.

7. The combination of a shaft, rings surrounding the same, spokes pivoted to said rings, and canvas supported by the spokes.

8. The combination, with canvas, of radial spokes, longitudinal wires carried by the spokes, short spokes carried by the wires 110 and extending through the canvas, and propeller blades secured to such short spokes on the outside of the canvas.

9. The combination of a longitudinal shaft, spokes adapted to extend radially 115 therefrom, longitudinal wires carried by the spokes, outwardly extending members carried by such wires and passing through the canvas of the balloon, and a propeller blade made of cloth and secured to such members 120 on the outside of the balloon and sewed to the balloon canvas.

10. In a balloon, the combination, with a lattice-work shaft built up of strips and braces, rings carried by such shaft, spokes 125 secured to said rings, and a canvas to which said spokes are secured.

11. In a balloon, the combination, with a shaft built up of strips and braces, spokes carried by said shaft, a canvas to which said 130

spokes are secured, said spokes being pivoted whereby the balloon may be collapsed.

12. In a balloon, the combination of a central shaft, a canvas surrounding the same, a 5 slideable head, and pivoted spokes allowing the canvas to be collapsed.

13. In a balloon, the combination of a central shaft, a canvas surrounding the same, a sleeve surrounding one end of the shaft in- 10 side of the canvas, a slideable head thereon, and pivoted spokes allowing the canvas to be collapsed.

14. In a balloon, the combination of a central shaft, a canvas surrounding the same, 15 a cylindrical sleeve surrounding one end of the shaft inside of the canvas, a gas inlet, air tight connections between the sleeve and gas inlet to facilitate the inflation of the balloon, and pivoted spokes allowing the 20 canvas to be collapsed.

15. In a balloon, the combination of a rotatable gas bag, a central lattice work shaft on which the same is mounted, trunnions extending from said shaft, hangers at the ends 25 of the balloon mounted on such trunnions, a car carried by said hangers, driving mechanism on the car, and means for communicating motion therefrom to the gas bag.

16. In a balloon, the combination of a gas 30 bag, of an internal air bag, an exit passageway therefrom, and a double-acting valve for said passageway.

17. In a balloon, the combination of a gas bag, of an internal air bag, an exit passageway therefrom and a double-acting valve for 35 said passageway, said valve comprising an outer member secured to the canvas, a ring closing thereagainst and an inner member closing against the ring from the opposite 40 side, and springs for holding the inner member against the ring and for holding the ring against the outer member.

18. In an air ship, a gas bag, a shaft extending longitudinally therethrough, a plurality of rings secured to said shaft, a series 45 of spokes radiating from each of said rings, disks at the outer ends of said spokes for attaching the gas bag to the outer ends of said spokes, stay wires connecting the outer ends 50 of certain of said spokes being attached to the respective disks to which said spokes are attached, diagonal stay wires connecting the outer ends of certain of the spokes at its disk with the outer ends of certain of the 55 spokes for the next adjacent disk, and longitudinal wires extending from one end of the gas bag to the other and connected with the outer ends of said spokes, whereby a rigid frame-work for the gas bag is provided.

19. In an air ship, a gas bag, a longitudinal shaft extending therethrough, a plurality of rings secured to said shaft, a series 60 of radial spokes attached to each of said rings, disk-like members for attaching the 65 gas bag to the outer ends of said spokes,

stay wires connecting the outer ends of certain of said spokes being attached to the disks to which said spokes are attached, diagonal stay wires connecting the outer ends of certain of said spokes in one series with 70 certain of the spokes in the next adjacent series, truss wires connecting the adjacent spokes in the same series, and longitudinal wires connecting the corresponding spokes in two adjacent series. 75

20. In an air ship, a gas bag, a shaft extending therethrough, a plurality of sets of radial spokes, means for attaching the gas bag to the outer ends of said spokes, a plurality of wires extending about said gas 80 bag, and a disk pivoted upon the outer ends of each spoke for securing the wires thereto.

21. In a balloon, the combination of a gas bag, short spokes projecting through the fabric of the bag and extending inwardly 85 from the bag only short distances, means for holding said spokes in upright position, and spiral vanes mounted on said short spokes.

22. The combination, with a canvas, running wires within the canvas, spokes extending 90 through the canvas and bearing at their inner ends on the running wires, and a propeller blade on the outer side of the canvas secured to such spokes.

23. In a balloon, the combination, with a 95 canvas, of longitudinal running wires within the balloon extending substantially parallel with the canvas and adjacent to it, short wire spokes bearing at their foot against such running wire and projecting 100 through the bag, and a propeller blade on the outer side of the canvas secured to such construction and secured to the canvas.

24. The combination of a shaft, a balloon surrounding the same, and pivoted supporting spokes connected with the shaft and the 105 balloon.

25. In an air ship, the combination with a shaft built up of strips and braces, of a canvas bag surrounding the shaft, sets of 110 frame members carried by the shaft and extending in substantially radial planes to the canvas, and a network of wires for reinforcing the canvas extending spirally, circumferentially and longitudinally about the gas 115 bag.

26. The combination, with a shaft and spokes, of a gas bag carried thereby, an internal air bag surrounding the shaft and adapted to compensate for variations of 120 pressure of the gas, means for bracing the gas bag, elastic cords within the gas bag and attached to the internal bag and to the means for bracing the gas bag, and means for rotating the structure described. 125

27. In an airship, a gas bag, a shaft extending therethrough, a series of radiating spokes secured to the said shaft, and a network of wires extending spirally, circumferentially and longitudinally about the gas 130

- bag, said wires being removably attached to the ends of the spokes.
28. In an air ship, the combination of a central shaft, hubs carried by said shaft, spokes radiating from said hubs, wires connected to the ends of said shaft and the outer ends of said spokes, and a movable ring at one end of the shaft to which the wires are attached.
- 19 29. In an air ship, the combination of a gas bag, a central shaft, hubs carried by said shaft, spokes radiating from said hubs, wires connected to one end of said shaft and passing over the outer ends of said spokes, slidable means at the other end of the shaft to which said wires are attached, and means exterior to the gas bag for moving said slidable means to tighten said wires.
- 20 30. In an air ship, the combination with a gas bag, of a central shaft, a ring attached to said shaft, a series of hubs mounted thereon, spokes radiating from said hubs and pivoted thereto, wires attached to said ring and attached to the outer end of said spokes, brace wires attached to the shaft and to the outer ends of some of said spokes, extending inwardly, and a slidable ring to which the inwardly extending ends are attached.
31. In an air ship, the combination with a gas bag, of a central shaft extending longitudinally therethrough, spokes pivotally attached to said central shaft and radiating therefrom, means for attaching said spokes to the gas bag comprising a flat plate having perforations and having ears punched therefrom, a pin extending through said ears and the spokes, and wires extending about the gas bag and having their ends attached to said plate through said perforations.
32. In an air ship, the combination of a gas bag, a shaft extending longitudinally through the same, a series of spokes pivoted and radiating from said shaft, means for attaching the outer ends of the spokes to the gas bag, wires attached to one end of said shaft and to the outer ends of said spokes, a ring slidably mounted on the other end of the shaft to which the ends of said wires are secured, and means for fastening said ring in position at the end of said shaft.
33. In an air ship, the combination with a gas bag, of a longitudinal shaft extending therethrough, a series of spokes pivoted to and radiating from said shaft, brace wires attached to the outer ends of said spokes, longitudinally movable means mounted on the shaft and to which said brace wires are attached within the gas bag, and means for holding said movable means in a position in which the brace wires are taut.
34. In a balloon, the combination of a gas bag, an internal air bag and an exit passage
- way therefrom communicating with the exterior of the gas bag, a frame for holding the balloon distended, and elastic means attached to said internal air bag and to said frame for holding the internal bag distended.
35. In a balloon, the combination of a gas bag, a longitudinal shaft extending therethrough, a series of spokes pivoted to and radiating from said shaft and attached at their outer ends to the gas bag, a sleeve surrounding the end of said shaft and having a closed outer end, and a slidable ring mounted on said sleeve to which said gas bag is attached whereby when the spokes are folded to the shaft said ring may slide along the sleeve permitting the bag to collapse.
36. In an air ship, the combination of a gas bag, a longitudinal central shaft extending therethrough, a series of spokes pivotally attached to said shaft and radiating therefrom and attached at their outer ends to the gas bag, said gas bag having its ends contracted toward the shaft, means at one end of the shaft attached to the gas bag for closing the contracted ends of the same, a sleeve surrounding the other end of the shaft having a closed outer end, a ring slidably fitting said sleeve to which the other contracted end of the gas bag is attached, and means for drawing said slidable ring along said sleeve to hold the gas bag distended.
37. In a balloon, the combination with a gas bag, of pivoted supporting spokes attached at their outer ends to the gas bag and flexible tension members passing around the balloon in different directions, means for securing them to the bag at some of their intersecting points, and means for securing them to the spokes at other intersecting points.
38. In a balloon, the combination with a gas bag, of a collapsible frame work within the gas bag, flexible tension members extending spirally around the balloon in different directions and extending from end to end thereof, and means for securing the flexible tension members to the collapsible frame work.
39. The combination, in a balloon having a central axis longer than its diameter, of a collapsible frame work within the bag, longitudinal flexible tension members extending from end to end of the balloon, tension members extending spirally along the gas bag, and circumferential flexible tension members, some of said tension members being secured at some of their points of intersection to the frame work.
40. In a balloon, the combination of a gas bag, a plurality of sets of radiating spokes for holding the bag distended, means adjacent the axis of the balloon on which said

sets of spokes are pivoted, and means for connecting the outer ends of the spokes of one set with the outer ends of the spokes of the adjacent set.

5 41. In a balloon, the combination with a gas bag, of sets of radiating supporting spokes for holding the gas bag distended, means pivotally carrying the inner ends of the spokes of each set, and tension members extending between the inner ends of one set of spokes and to the outer ends of the adjacent set of spokes independently of the bag.

10 42. In a balloon, the combination of a gas bag, of an internal air bag and a passageway communicating with the exterior of the bag, a frame for holding the balloon dis-

tended including radiating spokes, elastic means for holding the internal bag distended, and said bag having sleeves surrounding some of said radiating spokes.

15 43. In a balloon, the combination of a gas bag, an internal air bag, a passageway communicating with the exterior of the bag, a frame for holding the balloon distended having radiating spokes, said bag having sleeves surrounding some of said spokes.

In testimony whereof, I hereunto affix my signature in the presence of two witnesses.

OSCAR J. LAISY.
